CODE CALLING SELECTOR

Christian Miller, New York, N. Y., assignor to
 Edwards and Company, Inc., a corporation of
 New York

Application October 17, 1935, Serial No. 45,399

12 Claims. (Cl. 177—380)

This invention relates to an apparatus or mechanism for selectively sending or transmitting code-like signals and more particularly to apparatus or mechanism of that character frequently employed to transmit coded signal impulses to a number of signaling devices, usually audible, distributed throughout a building, factory, or the like.

One of the objects of this invention is to provide a simple and inexpensive selective code signal transmitting mechanism that will be of compact and fool-proof construction, dependable in action and capable of simplicity and ease and speed of control or actuation. Another object is to provide a signaling transmitter of the above-mentioned character that will have a wide range and appropriate flexibility of change of possible code signals, from which selection may be made, without correspondingly increasing production costs and without correspondingly complicating the mechanism. Another object is to provide a mechanism of the above-mentioned character in which selection of the desired code signal may be speedily effected in a simple manner and in which selection of the desired signal, usually corresponding to an individual person to be signaled, may be directly and most conveniently achieved manually.

Another object is to provide a mechanism of the above-mentioned character so constructed, however, that quantity production is facilitated, assembly of the various parts quickly and inexpensively achieved, and a minimum of individual parts utilized. Another object is to provide a construction of the above-mentioned character in which such disadvantages as are frequently attendant upon the employment of flexible electrical conductors for connecting a movable part may be dependably avoided and, moreover, in a thoroughly simple and practical way. Another object is to provide a mechanism of the above-mentioned type capable of easy, quick, and widely flexible manual control, and capable of meeting the widely varying and peculiar conditions of practical use. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of my invention,

Figure 1 is a front elevation of the completely assembled selective code signal transmitter, as it appears all ready for actual use;

Figure 2 is an end elevation, as seen from the right-hand end of Figure 1;

Figure 3 is a plan view of the operating and controlling mechanism as seen more particularly along the line 3—3 of Figure 1;

Figure 4 is a transverse or vertical sectional view as seen along the line 4—4 of Figure 1, and

Figure 5 is a fragmentary transverse or vertical sectional view as seen along the line 5—5 of Figure 3.

Similar reference characters refer to similar parts throughout the several views in the drawings.

The apparatus is preferably so constructed as to have its actual working parts preferably entirely encased and to that end I provide a casing construction preferably built up and having preferably certain parts thereof functionally interrelated with certain parts or features of the active mechanism itself, the latter, with its frame, and the parts of the casing being also by such interrelation arranged to facilitate manufacture and assembly.

Accordingly, the casing construction preferably comprises a unitary casing part generally indicated by the reference character 10 (Figure 1) and the part 10 is preferably so constructed as to comprise, as a unit, the top wall 11, the right-hand end wall 12, the bottom wall 13, and the left-hand end wall 14, being preferably and conveniently made of sheet metal and formed along or about those edges thereof facing the observer viewing Figure 1 with curved flanges 11^a, 12^a, 13^a and 14^a, respectively, the latter being in cross-section preferably as is better shown in Figure 4.

The casing part 10 is, furthermore, provided with a front plate 15 (Figures 1 and 4) and with a back or closure plate 16 (Figures 2 and 4) to complete the enclosure or casing in a manner described in detail hereinafter. The completed casing with the mechanism therein contained or thereto related, all as later described, may be secured in any suitable manner, as by screws, or the like, to a suitable base plate 17 (Figures 1, 2 and 4) which may be provided with rubber or other soft or padded abutments or legs 18 to engage, with a non-scratching or non-marring action, the table, desk, or other support or supporting surface therefor.

Contained within the casing part 10 is a frame comprising preferably two end plates 19 and 20 (Figure 3) rigidly secured together and held in

spaced relation by a suitable number of spacer members or cross-bars, illustratively three in number; these cross-bars are shown in Figures 3, 4 and 5 at 21, 22 and 23, are preferably round in cross-section, and may have the end plates 19 and 20 secured thereto as by suitable screws 24; thereby the end plates 19 and 20 are dependably held in substantial parallelism and the cross-rods 21, 22 and 23 likewise held in substantial parallelism. As a whole there is thus formed a light but strong frame dimensioned to be easily receivable within the casing part 10.

On the cross-rod 23 there is slidably and rotatably mounted a block-like member 25 (Figures 4 and 3) of insulating material, the block member 25 being provided with a sleeve 26 (Figures 3 and 4) which forms an elongated bearing for the block 25 with respect to the cross-rod 23. The sleeve 26 may be made of any suitable material, preferably of brass, bronze, or the like, and the fit between the bearing sleeve 26 and the rod 23 is sufficiently snug to prevent tilting of the block 25 and the parts carried thereby out of their intended plane of swinging or of rotation about the axis of the rod 23, but is sufficiently loose to permit the block 25, in a manner later described in detail, thereby conveniently moved manually either along the rod 23 or about the axis of the latter.

As is better shown in Figure 4, the block 25, though arcuate in shape throughout its major portion, has an upwardly and leftwardly extended portion that provides a flat supporting surface 25^a to which are secured two spring contact members 27 and 28, provided at their left-hand ends and on contiguous faces thereof with contact buttons 29 and 30, respectively, made of a suitable material, adapted to resist the disintegrating effects of sparking. The spring contact members 27 and 28 are extended to the right to form contactors 27^a and 28^a, respectively, the latter projecting to the right of the supporting block 25. Coacting with and spaced downwardly from the spring contactor 28^a is a companion spring contactor 31^a whose main body portion 31 parallels portions of the spring contact members 27—28. Spaced upwardly from the contactor 27^a is a similar contactor 32^a whose main body portion 32 likewise extends in parallelism with the spring contact members 27—28.

The parts 31, 28, 27 and 32 are spaced from one another by suitable spacers of which spacer 33 is of insulating material and spacers 34 and 35 may or may not be of insulating material, as may be desired. The entire assemblage including the somewhat stiffer backing spring members 37 and 38 for the spring contact members 27 and 28, respectively, is secured to the supporting face 25^a of the block 25 as by the screws 39, the latter being insulated from the various contact members and contactors in any suitable manner.

Thereby, there is provided the compact, strong and unitary assemblage of the contact springs and contactors with the rotatable and tiltable block 25, with the contactors 32^a—27^a, projecting to the right, electrically connected with the spring contact member 27 but insulated from the spring contact member 28 and the pair of contactors 28^a—31^a which are in electrical connection with the member 28 and which project to the right of the block 25. This entire assemblage may be slid along the spacer rod 23 and in any position along the latter it may be tilted,

all in the manner and for the purposes later described in detail.

The extreme left-hand end of the spring contact member 27 is provided with a tongue 27^b projecting, as shown in Figure 4, at a generally upward inclination, toward the left. If member 27 is now depressed by suitable downward depression of the tongue 27^b, the contact buttons 29—30 are brought into electrical and mechanical connection and thus the circuit connected to the contactors 32^a—27^a and 28^a—31^a may be correspondingly affected. Likewise, this circuit is affected upon release of the spring contact member 27 from its downwardly depressed position.

To effect actuation of the spring contact member 27, I provide a plurality of cam-like or toothed members 40 (Figures 3 and 4), with any one of which the switching or contact mechanism 27—28 may be selectively associated as is later herein described in detail, these members 40, hereinafter called "code members", are in the form of disk-like members whose peripheries are notched or toothed in accordance with the particular set or series of electrical impulses or circuit makes and breaks, which are to make up a particular signal. The devices 40 are preferably of sheet material, thereby lending itself to inexpensive manufacture as by punching or stamping; preferably they are of sheet metal.

In making up the members 40 I prefer to stamp, cut, or otherwise form them, uniformly, in the shape of a disk provided with a polygonal, illustratively hexagonal, central hole 41 (Figure 4) and with their peripheries provided with the same number of similarly shaped projections which are preferably shaped somewhat like the teeth of a saw. All of the members 40 are of the same outside diameter or pitch circle.

In any suitable manner, as by shearing, grinding, cutting, or like operations, I then remove from the disk members certain of the teeth, leaving such peripherally spaced teeth or sets or sequences of teeth that, when the particular disk member is uniformly rotated to sweep the teeth slowly past and into engagement with the tongue 27^b (Figure 4), the switch or contact mechanism 27—28 is correspondingly actuated.

Thus, referring to Figure 4 in which one of the code members 40 is shown in side elevation, it will be seen that the periphery of the member 40 is provided with two series or sequences T¹—T² and T³—T⁴ of equidistantly spaced teeth, each sequence or series numbering two sets of three teeth each.

If, therefore, the code member 40 of Figure 4 is rotated uniformly in clockwise direction and has the switch mechanism 27—28 operatively positioned with respect thereto in a manner later described in detail, a half rotation of the code member 40 causes the sequence T¹—T² of two groups of three impulses to be sent over the circuit controlled by the switch mechanism, representing, illustratively, the code signal "33". This is brought about by the sequence T¹—T². A subsequent half rotation effects a repetition of this action in that sequence of teeth T³—T⁴ is brought into action upon the switch mechanism to send the signal impulses corresponding to the code signal "33" through or over the circuit controlled by the switch mechanism.

Thus, a single rotation of the code member 40 of Figure 4 effects, in a single rotation, the actuation by the code member 40 of the contact springs 27—28 to make and break the circuit to

which the latter are related in sequences representing the signal "33" repeated once; thereby impulses may be sent over the circuit in question to effect, at one or more remote stations, the 5 production in any suitable manner, audibly, visually, or otherwise, of the signal "33" repeated once.

In Figure 3 I have diagrammatically indicated a number of remote stations or points where the 10 thus produced signal, to be reproduced, and these stations are indicated generally by the reference character S. They may take any desired form, as already above indicated, and illustratively they may be in the form of bells, buzzers, sounding horns, or the like. As indicated in Figure 3 these devices S are connected to a circuit comprising the conductors 44 and 45 in one of which, as in conductor 45, there is interposed a suitable source of electrical energy such as a battery 46. 15 The circuit represented by the conductors 44—45 is carried into the casing construction 10 in any suitable manner, preferably by way of a so-called two-conductor cord 47 which passes through an insulating and protective bushing 48, 20 preferably in the back plate 16 of the casing structure 10, whence the conductors 44—45 are secured, respectively, by binding nuts 50 and 51, and thereby electrically connected, to conductive bars 52 and 53, the latter being illustratively 25 of brass.

The bars 52—53 are preferably round in cross-section and are carried by and bridged across the frame plates 19—20, to which they are secured at their respective ends by nuts 54 (Figures 3 and 5) suitable insulating bushings and washers 55 being interposed between the nuts, rods, and frame plate members to insulate the bars 52—53 from each other and from the frame plates 19—20. The bus bars 52—53 may thus also 30 take part in mechanically holding the frame plates 19—20 and related parts in appropriate rigid spaced and assembled relation.

The bus bars 52—53, thus extending between the frame plates 19 and 20, are, moreover, positioned, as is better shown in Figure 4, so as to be engaged respectively by the pairs 32^a—27^a and 23^a—31^a of spring contact members projecting to the right of the insulating block 25, and to be received between these yielding contact members 35 when the latter, with block 25, are swung in clockwise direction and into the position shown in Figure 4. It is in that position, as already indicated above, that the upper contact spring 27 has its tongue end 27^b positioned to be actuated 40 by the teeth of the selected code member 40.

Though the block 25, with the parts carried thereby, may be slid along the cross-rod 23 in order to select in a manner hereinafter described, one of the code members 40 to actuate the spring 45 contacts 27—28, the bus bars 52—53 make it possible to bring the contacts into the above described electrical circuit at any point in the path of travel of the contact-carrying block 25 along its supporting rod 23.

The code members 40, provided with differently arranged sequences of teeth so that as many different signals may be transmitted as there are code members 40, are, as already above-mentioned, preferably of sheet metal and they are 50 mounted on a shaft 60 (Figure 4) to which they are non-rotatably secured in any suitable manner.

However, to secure certain important practical advantages, both by way of lowering cost of 55 manufacture and facilitating assembly and mak-

ing for reliability of operation, I prefer to give the shaft 60 a polygonal cross-section, illustratively hexagonal, as is shown in Figure 4, the hole 41 in the code members 40 being also hexagonal but larger dimensioned. Into the hole 41 of the code members 40 there is inserted, preferably with a somewhat tight or press fit, an insulating hub 61 (Figure 4) which is made preferably by cutting off short sections of hexagonal tubing of fiber, hard rubber, or other insulating material, the tubing being interiorly dimensioned to snugly receive therein the hexagonal shaft 60. The sections of tubing thus to form the hub members 61 are of an axial length equal to the thickness of the sheet metal of the code members 40. 10

The shaft 60 (Figure 3) is provided at its right-hand end with a shoulder 62 and at its left-hand end it is turned down and threaded as at 63, whereby it may receive a nut 64. 15

Onto the hexagonal portion of the shaft 60 the code members 40 are now all strung, each, as will now be clear, having a hexagonal hub member 61 (Figure 4) of insulating material; in thus stringing them onto the hexagonal part of the 20 shaft 60, however, the code members 40 are alternated with disk-like insulating washers 65 and a spacer 66 (Figure 3) also of insulating material and which conveniently and preferably is also a cut off short section of the above-mentioned hexagonal insulating tube. As is clearly shown in Figure 3, there is an insulating disk-like washer 65 on each side of each code member 40 with a hexagonal spacer member 66 between adjacent insulating washers 65. Thereby the 25 code members 40 are uniformly spaced apart at regular intervals, rotation of any code member relative to the shaft 60 is reliably precluded, while the stringing of all of the code members 40 onto the shaft 60 with the starting point of 30 all of the teeth sequences thereon all aligned is greatly facilitated and simplified. As appears in the illustrative showing of Figure 4, the code members 40 all have a gap in the teeth sequences along the lowermost peripheral portion thereof, 35 with respect to which portion the tongue 27^b of the contact spring 27 is initially positioned, as will later be made clearer; accordingly, so long as the shaft 60 with the code members 40 thereon is always brought back to its normal position of 40 rest, being that position shown in Figure 4, the above-mentioned gap in the teeth sequences provides an axially extending gap along which the contact spring end 27^b may be moved and properly positioned to select any one of the code members 40, and thereby it is always certain that the starting of the rotation of the shaft 60 will always properly start the transmission of the 45 selected signal. 50

Referring again to Figure 3, the tightening up 55 of the nut 64 onto the threaded portion 63 of the shaft 60 securely clamps all of the code members 40 with the insulating washers and spacers alternated therewith, between the shoulder 62 and the nut 64, insulating washers 65 being interposed between the endmost code members 40 and the shoulder 62 and nut 64, respectively. The assembly of the code members 40 with respect to the shaft 60 will thus be seen also to lend itself not merely to quick assembly but also to quick 60 disassembly in case it is desired to replace one or more of the code members 40.

The shaft 60 itself is preferably demountably supported in the frame structure which includes the frame plates 19—20. At its right-hand end 75

the shaft 60 is provided with a detachable coupling 67 which may take the form of a coaxial hub-like member within which may be received the end of a shaft 68, a suitable set screw or the like in the hub member 67 securing it to the shaft 68. The latter is a driving shaft and may be driven in any suitable manner, preferably, however, in the manner later described herein.

At its left-hand end the shaft 60 is provided with a suitable conical recess or "center" into which is projected and appropriately positioned the pivot end 69 of a pivot screw 70 threaded into the frame plate 19 and provided with a lock nut 71 to lock it and hence the pivot 60 in adjusted position.

With this mounting of the shaft 60 the latter, with the code members 40 may be taken quickly out of the interior frame structure, for such purposes as have illustratively been noted above.

As above indicated, the driving shaft 68 may, in so far as certain features of my invention are concerned, be driven in any suitable manner, but in order to achieve certain advantageous coactions and certain other results, the shaft 68 and hence the code members 40 are driven by a suitably manually controlled driving means which preferably takes the following form:

Mounted upon the interior frame structure and preferably secured to the plate 20 thereof and to the left of the latter, as viewed in Figure 3, is an auxiliary frame structure comprising spaced plates 70 and 71 shaped as is better shown in Figure 4, in which the plate 70 is seen in side elevation; the plates 70-71 are held in spaced relation by suitable spacers 72 and the resultant auxiliary frame structure 70-71-72 is secured to the end frame plate 20 as by screws 73 threaded into the plate 71, suitable washers or spacers 74 being interposed therebetween. Rotatably mounted in the plates 70-71 is the above-mentioned drive shaft 68, its left-hand end, as viewed in Figure 3, extending through the left-hand plate 70, thus to be exposed for connection thereto of the shaft 60 which carries the code members 40. The shaft 68, intermediate of the plates 70-71, is provided with a spur gear 75 (Figures 2 and 3) which meshes with a materially larger gear 76 rotatably supported on a shaft 77 which in turn is rotatably supported in the plates 70-71. To the right of the gear 76 is a spiral spring 78, one end of which, preferably the outer end thereof, is anchored to the frame 70-71 in any suitable manner, as by looping the end over one of the spacer studs 72, and the other or inner end of which is secured or anchored to the shaft 77. The spring 78 has its convolutions extend in such a direction that, if the shaft 77 is given a rotary movement in counter-clockwise direction, as viewed in Figure 2, the spring is tensioned or "wound up" to a commensurate extent.

Rigidly secured to the shaft 77 but to the left of the gear 76 (Figure 3) is a ratchet wheel 79 (see also Figure 2) and coacting with the ratchet wheel 79 is a pawl 80 pivoted in any suitable manner to the left-hand side face of the gear 76, a suitable spring biasing the pawl against the teeth of the ratchet wheel 79.

The right-hand end of the shaft 77, as viewed in Figure 3, extends beyond the plate 71 of the auxiliary frame and extends also through a suitable aperture in the frame end plate 20; juxtaposed thereto there is provided in the right-hand end wall 12 an opening 12^b through which, in the course of assembly, is inserted the hub 80^a of a crank arm 80 (Figures 3 and 2) whose outer end

is provided with a finger piece 80^b. The inner end of the hub 80^a slides over the right-hand end of the shaft 77 and a driving connection therebetween is effected, in any suitable manner, as by a set screw 81 (Figure 3), access to which, as with a screw driver, is gained through the rear opened end of the casing structure 10, the rear wall 16 being removable as is later described.

Accordingly, depression of the finger piece 80^b (Figures 3, 2 and 1) throughout a suitable arc 10 causes a corresponding rotary movement of shaft 77, thus to correspondingly tension the spring 78, and also causes a corresponding rotary movement of the ratchet wheel 79 whose teeth extend in such a direction that they by-pass the spring 15 pressed pawl 80 on the side face of the gear 76. Subsequent release of the lever 80 causes rotation of the shaft 77 in reverse direction but now under the energy released by the tensioned spring 78, the ratchet wheel 79 now driving the gear 76 20 through the pawl 80. Gear 76 drives the gear 75 and hence the driving shaft 68 and through it the shaft 60 with the code members 40 thereon.

In order to insure uniformity of speed of rotation of the code members, I provide a suitable 25 governor for controlling the rate at which the tensioned spring 78 can release its energy to rotate the code members 40. This governor preferably comprises a cup-shaped member 82 (Figures 3, 4 and 2) secured to the left-hand face of the 30 frame plate 70 in any suitable manner, and provided with an annular rim 83 against whose inner cylindrical surface bear two friction members 84-85 (Figure 4) made, for example, of a suitable fibrous material such as cotton, and carried in 35 the outer ends of the cylindrical weights 86 and 87, respectively. The weights 86-87 are slidably mounted on a two-armed spider whose arms 88 and 89 are 180° apart and whose hub 90 is secured to a shaft 91.

The shaft 91 is rotatably mounted in the auxiliary frame plates 70-71 (Figure 3) and has a small spur gear 92 (Figures 3 and 2).

Through suitable gearing of appropriate gear ratio, the shaft 91, and hence the governor 45 weights 86-87 are rotated or driven at a materially higher speed than the driving shaft 68, and this gearing may comprise a large gear 93 (Figures 3 and 2) mounted on the shaft 68 adjacent the inside face of the plate 70 to drive a 50 small gear 94 on a shaft 95 likewise rotatably supported in the frame plates 70-71. The shaft 95 in turn carries a large gear 96 which meshes with the gear 92 of the governor shaft 91, thus completing the governor drive gearing above-men- 55 tioned.

Accordingly, substantial uniformity of speed of the code members 40 with resultant accuracy of spacing of time intervals, as determined by the spacing between the teeth and/or teeth sequences 60 on the code members 40, is dependably assured. Should the spring 78 tend to drive the code members too fast, the resultant tendency is at once transmitted to the governor shaft 91 but in a greatly magnified manner and as a result of the 65 resultant tendency to increase the speed of rotation of the sliding governor weights 86-87, the latter are pressed against the rim 83 with a greater force, thus increasing the friction and thus restoring the speed to normal and thus promptly 70 correcting tendencies to depart from the latter.

The left-hand end of the shaft 77 is carried through and beyond the left-hand auxiliary frame plate 70 (Figures 3 and 4) and it has secured thereto, in the manner shown in Figures 3 75

and 4, a stop arm 97 which may coact with a stop pin or stud 98 secured to the outer face of the plate 70 and positioned in the path of rotary movement of the stop arm 97. Being anchored 5 to the shaft 71, the stop arm partakes of the same rotary movements as does the shaft 71 itself, and it is so positioned with respect to the shaft 71 and the stop stud 98 that it engages the latter, when shaft 71 and hence stop arm 97 are rotated by 10 the spring 78 (in counter-clockwise direction, as viewed in Figure 4), and stop the rotation of all of the parts at such a point that all of the code members 40 are brought to the position shown in Figure 4 in which, as earlier noted, the lower-most portions of the peripheries of the code 15 members 40 are devoid of teeth to provide for the gaps or spacings which represent the starting points of subsequent code or signal transmitting operations of the code members. The stop arm 97 in coaction with the stud 98 thus insures that 20 the code members 40 are always brought to a halt at a point such that subsequent signal-transmitting operations thereof are always properly started.

25 Preferably the spring 78 is so tensioned initially that it is not entirely "unwound" when this stop action of the parts 97-98 takes place; thereby I insure that the spring 78 will always bring the parts to the proper stopping and hence starting point.

30 The gear ratio of the gear train that drives the shaft 60 with the code members 40 thereon preferably bears a certain relation to the construction and action of the pawl 80 and ratchet wheel 35 79 (Figure 3). For example I may give the ratchet wheel 79 say ten teeth and thereby I make certain that the finger piece lever 80 (Figures 3 and 2) must be given* a manual rotation, in counter-clockwise direction as viewed in Figure 40 2, of at least one-tenth of a complete revolution and hence substantially 36° before the next tooth on the ratchet wheel 78 is brought into coaction 45 with the pawl 80; this gear ratio, furthermore, is such that, if the lever 80 is now released, the stored energy in the spring 78 starts driving the parts and is sufficient to give the shaft 60 carrying the code members 40 one complete revolution, during which the stop member 97 (Figure 4) is again returned to contact and stopping relation 50 with the stud 98. As earlier above noted, such a single complete revolution is adequate to cause the selected code member to transmit the corresponding signal twice in succession.

If, however, it is desired to cause additional 55 repetitions of the selected signal, the initial actuation of the lever 80 or even the subsequent actuation thereof, is caused to bring about a downward swinging thereof, as viewed in Figure 2, throughout twice the above-mentioned illustrative angle and hence throughout an angle of 60 about 72°; during such actuation the ratchet wheel 79 is rotated throughout a distance or angle of two of its teeth, the pawl being brought into coaction with the second tooth, and the resultant 65 driving of the shaft 60 causes the latter to partake of two uninterrupted complete revolutions, the selected code member thereby effecting the transmission of the signal four times in succession. Of course, the stop arm 97 has been swung 70 through twice the angle, being coaxial with the finger piece lever 80, so that its return movement under the action of the spring 78 is throughout a path twice as long, during which the shaft 60 partakes of two complete rotations as just noted.

75 The operator, due to the coaction of the parts

as just mentioned, therefore must always achieve a downward swinging of the lever 80 throughout at least either of two minimum angles corresponding respectively to one and two teeth on the ratchet wheel 79 if the angle of swing is less than the angle of one tooth, the lever 80, when released, simply returns to normal under the action of the spring 78. If the angle of swing is greater than the angle of one tooth but less than the angle subtended by two teeth, the lever 80 10 when released simply moves in reverse direction under the action of the spring 78 until the first tooth that has bypassed the pawl 80 is brought into engagement with the latter. In any case, the operator can always tell whether the angle of 15 swing is adequate either for a single rotation of the code members or two successive rotations thereof and this is accomplished preferably by giving the spring mounting of the pawl 80 sufficient tension that an easily audible "click" 20 results when a tooth of the ratchet wheel 79 bypasses the pawl 80. The operator therefore may guide his swinging of the operating lever 80 throughout the desired angle by noting the tell-tale click or clicks of the pawl. Thus, also, 25 improper actuation of a code member is dependably precluded and it is virtually impossible for the operator to garble a selected signal in its transmission.

30 As earlier above described, the insulating block 25 (Figure 4) that carries the spring contact members is slidable along the rod 23 to select, preferably in the manner later described in detail, the desired one of the several code members 40 on the shaft 60 (Figure 3); likewise it is tiltable 35 about the axis of the rod 23. To effect manually sliding or certain tilting movements of the member 25, the latter has secured thereto at its front edge, as viewed in Figure 3, and at its right-hand face, as viewed in Figure 4, a stud 101, preferably of metal and conveniently threaded into the hub portion of the member 25. It projects through the front wall 15 of the casing construction 10 for coaction with certain unique features later to be described in detail and at its outer end 40 it carries a knob or handle 102 whereby it may be easily grasped by the fingers of the hand and the member 25 manipulated.

45 Disregarding for the moment certain preferred controls of the sliding movement of the member 25 along the rod 23 and considering first the tilting movements of which it is capable about the axis of the rod 23, it is first to be noted that member 25 has secured to it a spring 103 (Figure 4) 50 preferably in the form of a leaf spring whose lower or unanchored end bears against the earlier above-mentioned cross-rod 22 of the interior frame structure. Spring 103 tends to swing the member 25 in counter-clockwise direction, as viewed in Figure 4, hence tends to swing the handle 102 upwardly. Moreover, and since the rod 22 extends throughout the length of the path of sliding movement of the member 25, the spring 55 103 may slide lengthwise of the rod 22 as the member 25 is slid along the rod 23, and thus proper action of the spring 103 is assured no matter what position that the member 25 is given lengthwise of the rod 23.

60 The spring 103 is thus always capable, when 70 permitted, to swing the member 25 in counter-clockwise direction (Figure 4), thereby to move the spring contact tongue 27^b out of the path of possible movement of the teeth on the code members 40 and also to move the two pairs of spring 75

contacts at the right of the member 25 out of engagement with the bus bar members 52, 53.

The under face of the upper left-hand portion of the member 25, as viewed in Figure 4, is provided with two notches 25^b and 25^c selectively cooperative with a rod 104 (Figures 3, 4 and 5) which has anchored to its ends links 106 and 107, thereby forming in effect a yoke, the lower ends of the links being apertured to receive therethrough the frame cross-rod 22 sufficiently loosely to permit the U-shaped yoke to pivot freely about the cross-rod 22.

In Figure 4 this yoke is shown so positioned that the rod 104 is seated in the notch 25^c of the member 25, thus holding the latter against rotation in counter-clockwise direction. A spring 108 (Figure 3) mounted and related to these parts, as is shown in Figure 5 and having its coils extending about the rod 22, acts yieldingly to move and hold the yoke and hence rod 104 in the position shown in Figure 4.

Thus, as viewed in Figure 4, the rod 104 tends to be moved in clockwise direction by the spring 108 while member 25 tends to be moved in counter-clockwise direction by its spring 103. By these interactions rod 104 may be held seated in either notch 25^c or notch 25^b (Figure 4) of the member 25, member 25 with the parts carried by it assuming corresponding positions of tilt about the axis of rod 23.

Rod 104, as is better shown in Figure 3, extends parallel to the rod 23 along which the member 25 with its spring contacts is slidable and it is of sufficient length to insure that it can and will 35 coact with either of the notches in the member 25 irrespective of what position the latter assumes lengthwise of its supporting rod 23. At its left-hand end, as viewed in Figure 3, the rod 104 has extending underneath it and engaging it a release 40 cam 109 whose hub 110 is carried by and freely rotatable on the frame cross-rod 23 (see Figures 3 and 5). Threaded into the hub 110 is a stud or rod 111 which projects through a suitable slot 112 (see Figure 1) in the front wall 15 of the casing structure 10, whereby the hub and its cam 109 are prevented from sliding lengthwise of the rod 23 but may be given a rotation to the extent permitted by the vertical dimension of the slot 112, the stud 111 having threaded or otherwise detachably secured thereto at its outer end (Figure 5) a knob or handle 113 for manipulating the cam 109.

The cam 109 is shaped substantially as shown in Figure 5 and it as well as the handle 113, is held in the position shown in Figure 5 by the locking rod 104 which is, at this stage, engaged in the notch 25^c of member 25 and hence is related to the latter as shown in Figure 4. If, however, the knob 113 (Figure 5) is depressed, the cam member 109 cams the rod 104 to the right against the action of spring 108, thus effecting a counter-clockwise movement of the rod 104, as viewed in Figure 4, and thereby forcibly moving it out of the notch 25^c. Since, however, spring 65 103 (Figure 4) of the member 25 always tends to swing the latter in counter-clockwise direction about the rod 23, it causes the notched edge of the member 25 to follow up the change in position of the member 104 and to maintain contact with the latter, the locking rod 104 becoming by this continued follow-up movement seated in notch 25^b; this latter action is accompanied by a counter-clockwise swinging of the member 25 about its supporting rod 23, thereby bringing the contact 70 tongue 17^b out of the path of movement of the

teeth of the code member or members and also disengaging the two pairs of spring contacts from the bus bars 52-53.

The above described coaction of the springs 108 and 103 (Figures 4 and 5) with their related parts insures the holding of the member 25 in this position. If, now, however, member 25 is tilted about the rod 23 by depressing the handle 102 (Figure 4) such action effects a disengagement of the notch 25^b from the rod 104, the spring 108 of the latter now causing it to follow up the notched edge of the member 25 with the result that the locking rod 104 becomes again seated in the notch 25^c, the member 25 and related parts thereby becoming positioned and held and locked as shown in Figure 4.

However, in accordance with certain other coacting features of my invention, the sliding or tilting movement of the member 25 (Figure 4) with the contact members carried thereby is preferably effected only under certain definitely controlled conditions, thereby making for foolproof manual operation or control of the apparatus and achieving other important advantages. In this connection certain features of the front wall of the casing structure 10 (Figures 1 and 4) through which the control levers or handles 101-102 and 111-113 project, as already above mentioned, will be stated. This front wall member 15 is preferably of sheet metal, is generally of rectangular shape, and is dimensioned so that it is readily receivable into the casing structure 10 from the rear thereof (the left-hand end as viewed in Figure 4) and is of sufficient extent to be brought into abutting relation to the inner ends of the curved flange portions 11^a-12^a-13^a-14^a of the wall portions 11-12-13 and 14, respectively (see Figures 1, 4 and 3). Preferably, this front wall plate 15 is secured to the above-described frame structure which, as is now clear, comprises the frame plates 19-20 (Figure 3) and the connecting cross-rods, such as the rods 21, 22, 23, etc. (Figure 4). Conveniently, this front plate 15 may be secured to the frame plates 19-20 (Figure 3) as by sheet metal angle members 115 and 116 45 whose webs or flanges may be secured in any suitable manner, illustratively as by spot welding, to the plates 19-15 and 20-15, respectively. Moreover, and as better appears in Figure 4, the three plates 19, 15 and 20 have their lower edges 50 in the same plane and hence these edges may directly engage and rest upon any suitable supporting surface when the interior frame with the parts carried thereby is out of the casing structure 10 or upon the bottom wall 13 (Figure 4) 55 when the frame structure with its parts is inserted into the casing structure 10.

In this front plate or wall 15 I provide a horizontally extending slot 117 (see Figures 1 and 4), the length of the slot being commensurate with 60 the extent of sliding movement of the contact-carrying member 25 along its supporting rod 23 (Figures 3 and 4).

It is through slot 117 that the rod or lever arm 101 (Figure 4) that carries the knob 102 for controlling the sliding and tilting of the member 25, extends, and the slot 117 is of sufficient length to accommodate the lever arm 101 throughout the range of sliding movement of the lever 25 necessary to traverse the contact members 27, 28 with 65 respect to the maximum number of code members 40 (Figure 3) with which the shaft 60 is provided.

The upper edge 118 (Figure 1) of this slot 117 is preferably straight and is at such a height 70 that the lever arm 101 (Figure 4) is still well ac- 75

commodated in the slot 117 when the member 25 assumes its tilted position in which the lock arm 104 is seated in the notch 25^b (Figure 4), that being the position, it will be recalled, in which the spring contact tongue 27^b is held out of the path of movement of the teeth on the code members 40 and in which the right-hand pairs of contact springs are mechanically and electrically disconnected from the bus bars 52-53. Accordingly, with the knob 102 in its corresponding uppermost position, undue movement beyond that position being prevented by the straight edge 118 of the slot 117, the knob or handle 102 may be grasped by the hand and moved to the right or the left within the range permitted by the length of the slot 117, the member 25 (Figures 4 and 3) with the parts carried thereby being correspondingly slid along the supporting rod 23.

Now the lower edge of the slot 117 (see now Figure 1) is toothed, being provided with teeth 119 having therebetween spaces 120, the spaces 120 being spaced center to center just as are the code disks or members 40 (Figure 3) on the shaft 60 and also alined with the latter. Thereby there is provided a slot 120 allocated to and alined with respect to each one of the code members 40 on the shaft 60. The slots 120, moreover, are of a width snugly to accommodate therein the lever arm or handle shank 101 (Figures 4 and 3) if the latter is pushed downwardly against the action of the spring 103 (Figure 4). Since, as appears from Figure 3, the shank or stud 101 on the member 25 is alined with or is on the center line of the spring contact members 27 and 28, the entry of the shank 101 into a selected slot 120 insures that the spring contact members 27-28 and particularly the contact tongue 27^b (Figure 4) become alined with respect to and associated with only one code member 40, that being the one to which the particular slot 120 is juxtaposed or allocated. It thus becomes impossible to set the spring contact members in a position where the contact tongue might or can be actuated at the same time by the teeth of two or more code members. Moreover, this feature insures such nicety and precision of positioning of the spring contact that it is possible greatly to decrease the spacing between code members 40 and thus greatly to increase the number of the latter per unit length of the shaft 60 than would otherwise be the case.

The bottoms of the slots 120 (Figure 1) are alined along a line parallel to the axis of the supporting rod 23 or parallel to the upper edge 118 of the slot 117 so that uniformity of limiting action takes place. Moreover, the depths of the slots 120 are such that the member 25 (Figure 4) may be swung by depressing the knob 102 throughout an angle just sufficient to bring the contact tongue 27^b into the path of the teeth of the selected code member 40, to bring the two pairs of spring contacts into good mechanical and electrical engagement with the bus bars 52-53, and to permit the lock bar 104, under the action of its spring 108 (Figures 4 and 5) dependably to follow up the contour edge of the member 25 and to ride out of the recess 25^b and into the recess or notch 25^c, this latter action causing the locking yoke dependably to hold the member 25 and its related parts in these positions, all as shown in Figure 4.

The height of the teeth 119, however, bears a certain preferred relation to certain other parts in order to achieve certain other important advantages. The upper ends of the teeth 119 (Fig-

ure 1) are alined along a line parallel to the axis of the supporting rod 23 (Figure 4) or parallel to the upper straight edge 118 (Figure 1) of the slot 117 and this alinement or line is at such a spacing downwardly from the straight edge 118 as to restrict the extent to which the knob 102 may be held downwardly away from the edge 118 as the knob 102 with the member 25 and related parts is moved to the right or left.

This restriction is such that, turning now to Figure 4, it is assured that the block 25 cannot be slid along the rod 23 in such a tilted position that the contact tongue 27^b crosses the path of movement of the teeth of the code members 40, whether the latter are standing still or rotating. Thereby, freedom of sliding movement, necessary to select the proper code member for coaction with the spring contacts, is assured, and colliding of a spring contact or a contact tongue with a code member or teeth of a code member is dependably precluded.

Over the front face of the front plate 15 (Figures 1, 4 and 3) is secured a plate 122, as by screws 123, whereby the plate 122 is detachably secured in place. Plate 122 is provided with a horizontally extending slot 124 which frames in, as it were, the slot 117 of the plate 15 with its teeth 119 and slots 120. If desired, its vertical end edge and its upper horizontal edge may coincide with the corresponding edges of the slot 117 and such a relation is shown in Figure 1. Thus, the control knob or lever 102 is accessible through this auxiliary plate 122. Similarly, the latter has a vertically extending slot 125 which mates with the slot 112 in the plate 15 (Figures 1 and 5) to accommodate the shank 111 of the cam 109 and again to leave the operating knob 113 accessible at the front of the front wall.

Spaced upwardly from the horizontal slot or opening 124 (Figure 1) in the auxiliary plate member 122 is a rectangular opening or window-like aperture 126, the intervening strip 127 of the sheet metal of the plate 122 being marked off in any suitable manner, as by stamping or impressing, into areas 128 generally rectangular in shape but each terminating at its lower end in a point or apex, substantially as shown in Figure 1. There is one such marked out area 128 for each slot 120 and hence for each code member 40 and, as shown in Figure 1, each area 128 is on the vertical center line of the slot 120 to which it is juxtaposed or allocated. The apex or point at the bottom of each member 128 thus points directly at the slot or recess 120 to which it is allocated.

In each area 128 is printed, stamped, impressed, or otherwise indicated, the numerical number or code according to which the teeth of its allocated code member are cut or arranged. In Figure 1 illustrative code numbers are indicated. Thus, reading from left to right, the code numbers 60 identifying the corresponding code members 40 (Figure 3) with respect to which the contact-carrying member 25 may be selectively set, through the mechanisms and coactions above described, will be seen to be "121", "2", "3", "4", etc. 65

Referring now to Figure 4, it will be noted that the front plate 15 is pressed rearwardly (to the left) as at 130 to form a rectangular seat or recess which is a little larger in both length and breadth than the opening or window 126 (Figure 1) in the auxiliary plate 122; in this recess 130 is seated a cardboard sheet 131 covered over by a transparent member 132 which may be of Celluloid, glass, or the like, these parts being held in the recess by the auxiliary plate 122. The paper or 75

cardboard sheet 131 is ruled off (see Figure 1) by parallel lines 133 inclined at an angle substantially as shown and forming in effect inclined extensions of the areas 128 above-mentioned. In 5 the spaces between successive lines 133 are written, printed, or lettered the names of the different individuals to whom a code number has been allocated or assigned. The sheet 131 will be seen to be readily accessible since it may be 10 easily slid out of its seat 130 when the plates 15 and 122 (Figures 1 and 4) are separated upon loosening the screws 123. Thus, the names or other indicia which it bears may be easily 15 changed, applied, added to or subtracted from, 15 and the sheet 131 put back in place.

The entire mechanism, as above already noted, will thus be seen to be carried by an internal frame with which, for greater convenience in assembly and construction, the front plate 15 and 20 its coacting parts are secured. With the handle 80 removed from this internal frame and structure, the latter may be slid into the casing through the open rear end (the end normally closed by the back plate 16 of Figures 3 and 4). 25 Suitable screws 134 (Figure 4) are passed through suitable openings in the base 17 and are threaded into suitable ears or lugs 135 that extend horizontally from the bottom edges of the main frame plates 19-20. Thereby the internal frame 30 with the mechanism is held in assembled relation to the casing construction and the front plate 15 caused snugly to engage the curved or flanged edges 11^a, 12^a, 13^a, 14^a and close the otherwise open end of the casing structure. 35 Thereby the shaft 77 (Figure 3) becomes juxtaposed to the hole 12^b in the side wall 12 and through the latter the hub 80^a of the crank lever 80 may be slipped onto the shaft 77 and the set screw 81, operated by a screw driver from the 40 rear open end, driven home. The rear cover plate 16 may then be put in place being secured by screws 145 (Figures 2 and 3) threaded into ears or lugs extending forwardly from the back plate 16 and receivable interiorly of the casing 45 construction. The back plate 16 may be thus assembled after the cord conductor 47 has already been put through the bushing 48 therein.

Accordingly, if the operator is called upon to 50 signal an individual by way of the various signaling devices S of Figure 3, the operator grasps the handle 102 (normally in its uppermost position) and slides it along the slot 117 (Figure 1) until it is brought opposite the lower pointed edge of the area 128 which forms the downward continuation of that space between two of the lines 55 133 that bears the name of the individual to be signalled.

Having done that, it being borne in mind that 60 the handle 113 (Figures 1 and 5) is normally in its lowermost position and that the stop bar 104 (Figure 4) is engaged in the recess or notch 25^b, the operator next pushes the knob or handle 102 downwardly, thus tilting the member 25 (Figure 4) into the position shown in Figure 4 to bring 65 the contact tongue 27^b in the path of movement of the teeth of the selected code member 40 and to bring the two pairs of contact springs 32^a-27^a and 28^a-31^a (Figure 4) into mechanical and electrical engagement with the bus bars 52-53, respectively; the downward movement of the knob 70 102 carries the shank 101 (Figure 4) downwardly into a slot 120, as already above described, thereby insuring that the contact tongue 27^b is properly aligned with respect to the selected code member and insuring that the contact springs are 75

dependably held in a position free from engagement therewith by an adjacent code member.

As the contact-carrying member 25 is moved into the above-described position as shown in Figure 4, the lock bar 104 rides out of the recess 5 25^b and into the recess 25^c, thus holding the parts in their above-described position, in the manner already above described in detail. At the same time the lock bar 104 (Figure 5) swings the knob 113 into its uppermost position, due to the lock 10 bar 104 engaging the cam member 109.

Thus, the contact springs 27-28 (Figure 4) are dependably positioned and locked in such position for proper coaction with the selected code member; movement of the member 25 and hence 15 of the contact springs is definitely precluded by the interaction of the shank 101 with its slot 120 and due to the coaction of the lock bar 104. The shank 101 substantially bottoms in its slot 120, thus preventing further clockwise swinging of the 20 member 25 (Figure 4) while the lock bar 104 prevents counter-clockwise swinging thereof. And the relatively snug fit of the shank 101 in the slot 120 holds the member 25 and the parts carried by it against movement lengthwise of the 25 supporting rod 23.

Not only are the contact springs 27-28 thus 30 reliably held in proper coacting relation to a selected code member 40 but also the contact springs 27-28 become thereby dependably connected to 35 the circuit 44-45 (Figure 3) through the engagement of the two pairs of contact springs with the bus bars 52-53. Accordingly, the spring contacts 27-28 are cooperatively related to the signaling circuit and, it will be noted, I am enabled 35 to accomplish this while eliminating the many mechanical, electrical and other disadvantages that accompany the use of long flexible conductors.

Next the operator pushes down the lever 80 40 (Figures 1, 2 and 3) and if it is desired that the signal be sent twice, the angle through which the lever 80 is thus swung is that angle corresponding to the termination of the first "click" sounded by the pawl 80 (Figure 3). If it is desired to 45 send the signal four times in succession, the lever 80 is swung through twice this angle, an angle determined by the second click sounded by the pawl 80. The rotation of the shaft 60 with the code members 40 ensues as was above described 50 in detail, the teeth of the selected code member coacting with the spring contacts 27-28 to send the corresponding current impulses over the circuit 44-45.

In the illustrative embodiment, the shaft 60 55 which carries the code members 40 makes one revolution in the one case and two complete revolutions in the second above-mentioned case, each time being brought to a halt by the stop members 87-98 and always at the proper starting position. 60 These cycles may be repeated at will by the operator who again actuates the lever 80 as may be desired.

On the other hand, if it is desired to interrupt 65 the sending of the code signals, all the operator need do is push down the knob 113 (Figures 1, 3 and 5), thereby causing the cam or lever arm 109 (Figure 5) to trip the lock arm 104 out of the notch 25^c (Figure 4) in the member 25, thereby causing the spring 103 to swing the member 70 25 with the contact members carried thereby in counter-clockwise direction as viewed in Figure 4, the lock arm 104 engaging in the recess 25^b and being held in that position and thereby holding also the member 25 with its contact members, 75

and also the knob 102, in their normal or ineffective position. Thus, the contact spring 27 may at any time be tripped out of operative relation to the selected code member 40 and either during the sending of a signal or after the completion of the transmission of code impulses. In either case, the mechanism is thereby set for subsequent actuation, in a manner that will now be clear in view of all of the foregoing.

10 In this latter connection it might be noted that the manual actuation or control of the mechanism is entirely foolproof. For example, the slot 117 (Figure 1) and related parts, such as the height of the teeth 119, insures that the member 15 25 (Figure 4) with its spring contacts 27-23 cannot be given a sliding movement lengthwise of the rod 23 unless it is so positioned that colliding or interference of the spring contact or contacts with the code wheel or wheels cannot 20 take place, and this, moreover, irrespective of whether the code wheel or wheels be stationary or rotating. Furthermore, the lock arm 104 and its control knob 113 are preferably arranged, as in the illustrative embodiment, so that they must 25 first be actuated in releasing direction before the selector knob 102 can be actuated; this insures that the member 25 assumes its ineffective position, namely, tilted in counter-clockwise direction from the position shown in Figure 4, and that 30 this tilted position, dependably limited by the coaction of the lock bar 104 with the notch 25^b, is first achieved before sliding movement of the member 25 with its spring contacts can be started.

Furthermore, the interrelation of the selector 35 knob 102 (Figure 1) with the slots 120, the code directory 128, 128, etc., and the name or place directory 133, 133, etc., makes for speed and simplicity in making a selection and insures minimum occurrence of error.

40 Furthermore, the apparatus will be seen to be compact, simple and reliable in construction and operation, readily accessible for replacement, rearrangement, adjustment or repair, and otherwise well adapted to meet the varying conditions of 45 hard practical use, and it will thus be seen that there has been provided in this invention an apparatus in which the various objects above noted together with many thoroughly practical advantages, are successfully achieved.

50 As many possible embodiments may be made of the above invention and as many changes might be made in the embodiment above set forth, it is to be understood that all matter hereinbefore set forth, or shown in the accompanying drawings, 55 is to be interpreted as illustrative and not in a limiting sense.

I claim—

1. In a signaling apparatus having a plurality of rotatable coded cam members and contact 60 means to be operated thereby, in combination, a rotatably mounted shaft of polygonal cross-section, a plurality of metal coded cam members, each apertured to be received on said shaft and each having mounted in its aperture an axially 65 short section of a tube of insulating material whose opening is of polygonal cross-section sufficient to snugly receive therein said shaft, and means spacing adjacent coded cam members axially from one another.

70 2. A construction as claimed in claim 1 in which the apertures in the coded cam members are also of polygonal shape and in which the exterior shape of said tubular sections is of similar polygonal shape and received within said apertures, whereby said shaft, said insulating sections

and said cam members are non-rotatably assembled.

3. In signaling apparatus, a sub-assembly for insertion into a casing structure open at a face thereof, comprising, in combination, a frame structure insertable into said casing structure, said frame structure comprising two end plates with a plurality of tie-rods connected to said end plates and holding them in spaced relation and a closure plate extending parallel to said tie-rods and forming a closure for the open face of said casing structure when said frame structure is inserted into the latter, said frame structure carrying signaling mechanism which includes at least a manually operable member projecting through said closure plate, carrier means slidably and tiltably mounted on one of said tie-rods, means connecting said manually operable member to said carrier means whereby it is movable with respect to said closure plate lengthwise in response to sliding movement of said carrier means and transversely in response to tilting of said carrier means, said closure plate having aperture means through which said member projects, and which signaling mechanism includes another manually operable member projecting through an aperture in said closure plate and locking and releasing means movably supported by another of said tie-rods and capable upon movement into one position to hold said carrier means in the position to which it had been moved by said first-mentioned manually operable member and upon movement into another position to release said carrier means for movement out of the position into which it had been moved by said first-mentioned manually operable member, and means forming an operative connection between said second-mentioned manually operable member and said locking and releasing means.

4. In signaling apparatus, a sub-assembly for insertion into a casing structure open at a face thereof, comprising, in combination, a frame structure insertable into said casing structure and having a closure plate for closing the open face of the latter when said frame structure is inserted into said casing structure and two end plates extending at right angles to said closure plate and a plurality of cross-tie-rods connected to said end plates, said frame structure carrying electric signaling mechanism which includes a carrier means for controlling the latter, means movably supporting said carrier means upon one of said tie-rods for movement therealong relative to said closure plate, a manually operable member having connection with said carrier means, said member projecting through said closure plate for actuation from the exterior of said casing structure, said closure plate being apertured in a direction lengthwise of said tie-rods whereby said manual member may be moved lengthwise of the latter and hence said carrier means moved along its tie-rod, means insulating at least one of said tie rods from said end plates, contact means movable with said carrier means and coacting with said insulated tie rods as said manual member is positioned along said aperture.

5. In a signaling apparatus having a switching means, in combination, a frame structure comprising two spaced end plates and a plurality of cross-tie-rods for holding said plates spaced, motive means carried by said frame, a shaft of polygonal cross-section having mounted thereon a plurality of metal coded cam members which are apertured to be received on said shaft and each

- of which has mounted in its aperture an axially short section of a tube of insulating material whose opening is of polygonal cross-section sufficient to receive therein said shaft, each of said 5 cam members having a signal-starting point means detachably mounting said shaft with respect to said frame structure for rotation about an axis parallel to at least one of said tie-rods and including a detachable driving connection 10 with said motive means, whereby said shaft may be quickly removed from said frame structure for rearrangement or replacement of said coded cam members lengthwise of said shaft and the signal-starting points of said cam members brought into and held in appropriate alinement 15 lengthwise of said shaft by properly relating said polygonal openings to said polygonal shaft, and supporting means for said switching means mounting the latter to said one tie-rod for movement lengthwise of the latter and substantially parallel to said shaft and to said alinement of said signal-starting points of said coded cam members, whereby said switching means may be 20 selectively positioned with respect to said code members.
6. In a signaling apparatus having a switching means, in combination supporting frame means comprising two spaced end members and a plurality of cross-tie-rods for holding said end members in spaced relationship, mounting means for said switching means for supporting it upon one of said tie-rods for selective movement lengthwise thereof, a shaft having a polygonal cross-section and having strung thereon a plurality of 25 coded cam means each having a signal-starting point and which have apertures to substantially match the polygonal cross-section of said shaft whereby their signal-starting points may be properly aligned lengthwise of said shaft and relative 30 to said selective movement of said mounting means and said cam means are non-rotatably related to said shaft, and means comprising readily demountable bearing means carried by said frame means for rotatably supporting said shaft in a position to present said cam means with 35 their aligned signal-starting points to selective co-action with said switching means according to the position of said mounting means along said one tie-rod and whereby said shaft with its cam means may be readily demounted for replacement 40 or rearrangement of said cam means.
7. In a signaling apparatus having a switching means, in combination, means forming a main support, carrier means for said switching means, means movably mounting said carrier means for movement relative to said main support and along a certain path whereby said switching means partakes of similar movement, a metal shaft of polygonal cross-section having strung 45 thereon a plurality of metal coded cam members each of which has a signal-starting point and has a bushing of insulating material whose aperture is of a shape to substantially match the polygonal cross-section of said shaft, whereby 50 said cam members may have their signal-starting points alined and so maintained, and bearing means having readily detachable connection with said shaft for rotatably supporting it from said main supporting means for rotation to present 55 said cam members to said switching means along the path of movement thereof as determined by the aforesaid path of said carriers means and whereby said shaft may be readily removed for rearrangement or replacement of said cam members.

8. In a signaling apparatus having manually movable contact means with means for guiding said means along a certain path of movement and manually controlled means for selectively positioning said contact means at any one of a plurality of stations along said path, the combination of a plurality of coded cam members each having a signal-starting point and a hole, and a shaft member onto which said cam members are strung by way of their holes, the cross-section of said shaft member fitting the shape of said holes and the holes and the shaft cross-section being shaped to effect non-rotatable engagement between the shaft and said cam members, whereby, as said cam members are strung onto said shaft, the signal-starting points of all of them may be alined longitudinally of said shaft member, said cam members being spaced according to the spacing of said plurality of stations along said path, with readily releasable means for holding said cam members from movement along said shaft member, and readily releasable bearing means carried by said apparatus for rotatably supporting said shaft member in alinement with said path and with said cam 10 members respectively juxtaposed to said plurality of stations, whereby said shaft may be readily removed for rearrangement or replacement of said cam members.
9. In a signaling apparatus having manually movable contact means with means for guiding said means along a certain path of movement and manually controlled means for selectively positioning said contact means at any one of a plurality of stations along said path, the combination of a shaft of polygonal cross-section having strung thereon a plurality of apertured metal coded cam members each of which has a signal-starting point and has mounted in its aperture an axially short section of a tube of insulating 15 material whose opening is polygonal and substantially matches the polygonal cross-section of said shaft whereby said cam members may have their starting points alined and so maintained lengthwise of said shaft and said cam members are 20 non-rotatably and insulatingly mounted on said shaft, the latter having means for holding them against axial movement, motive means related to said apparatus, and readily disconnectable means rotatably mounting said shaft in said apparatus 25 in a position to aline said cam members and their alined starting points with said path and respectively with said plurality of stations and including a disconnectable driving connection with said motive means.
10. In signaling apparatus, in combination, a frame structure comprising two spaced end plates and a plurality of cross-tie-rods for holding said plates spaced, rotatable means supported by said frame structure and carrying a plurality of code cam members alined in the direction of one of said tie-rods, switching means, carrier means slidably mounted on said one tie-rod for movement in the direction of alinement of said code members, means mounting said switching means on said carrier means for movement with the latter along said one of said tie-rods, whereby said switching means may be selectively positioned with respect to any one code member by sliding said carrier means along said one tie-rod, and means for 30 thereafter shifting said carrier means in a direction to move the switching means carried by it into operative relation to the selected code member, a stop bar extending lengthwise of the path of sliding movement of said carrier means, and 35

means pivotally mounting said stop bar with respect to another of said tie-rods for movement of said stop bar relative to said carrier means to hold the latter and hence said switching means in shifted position and against movement out of said operative relation to the selected code member.

11. In a signaling apparatus having switching means, in combination, a frame structure comprising two spaced end plates and a plurality of cross-tie-rods for holding said plates spaced, rotatable means supported by said frame structure and carrying a plurality of code cam members alined in the direction of one of said tie-rods, carrier means slidably mounted on said one tie-rod for movement in the direction of alinement of said code members, means mounting said switching means on said carrier means for movement with the latter along said one tie-rod, whereby said switching means may be selectively positioned with respect to any one code member by sliding said carrier means along said one tie-rod, means for thereafter shifting said carrier means in a direction to move the switching means carried by it into operative relation to the selected code member, means for insulating another of said tie-rods from said end plates, said

carrier means carrying contact means electrically connected to said switching means and movable into or out of electrical contact with said insulated tie-rod in accordance with the shifting movement of said carrier means.

12. In signaling apparatus, in combination, a frame structure comprising two spaced end plates and a plurality of cross-tie-rods for holding said plates spaced, rotatable means supported by said frame structure and carrying a plurality of code cam members, switching means, supporting means for said switching means, means mounting said supporting means for movement substantially parallel to the axis of said rotatable means whereby said switching means may be selectively positioned with respect to said code members, means whereby said switching means may be moved in a direction radially of a selected code member and into or out of coacting relation thereto, a stop bar extending substantially parallel to the path of sliding movement of said supporting means for holding said switching means in coactive relation to the selected code member, and means pivotally mounting said stop bar from one of said tie-rods.
